Patented July 22, 1919.

FIG. 1.

FIG. 2.

FIG. 3.

Inventor

Bruno Pelz.

By his attorney

Maurice Block

UNITED STATES PATENT OFFICE.

BRUNO PELZ, OF NEW YORK, N. Y.

MOVABLE-EYE DOLL.

1,310,925.

Specification of Letters Patent. Patented July 22, 1919.

Application filed October 24, 1918. Serial No. 259,479.

To all whom it may concern:

Be it known that I, BRUNO PELZ, a citizen of the United States of America, residing at New York city, Bronx county, State of New York, have invented certain new and useful Improvements in Movable-Eye Dolls, of which the following is a full, clear, and exact description.

This invention relates to dolls and has for 10 an object to provide an improved device to support movable eyes, or eyes that will open and close. One of the objects of my invention is to provide an inexpensive mounting, frame or holder for eyes that will open or 15 close, that can be easily inserted into proper position within the head of a doll. A further object is to provide means whereby the eyes will be properly positioned relatively to the eye openings in the head. One of the 20 difficulties encountered in the assembling or placing of movable eyes in dolls is that the eyes are liable to be positioned out of proper alinement with the openings in the head and it is one of the objects of my invention to 25 provide means to obviate this difficulty.

I will now proceed to describe in what manner I accomplish the above results, and finally claim the novel features of my invention, reference being had to the accompanying drawing, wherein—

Figure 1 is a cross sectional view of a doll head looking from the back embodying my improvements;

Fig. 2 is a longitudinal sectional view, the 35 section being taken on a line 2—2 in Fig. 1;

Fig. 3 is an enlarged fragmentary sectional detail view, the section being taken on a line 3—3 in Fig. 2, illustrating one of the anchorage members for the support or 40 frame for the eyes;

Fig. 4 is a similar view, the section being taken on a line 4—4 in Fig. 1, illustrating the alining block for the support for the eyes;

Fig. 5 is a perspective view of one of the 45 eye-members; and

Fig. 6 is a sectional plan view, the section being taken on a line 6—6 in Fig. 1, illustrating the manner of applying the 50 counterweight for the eye-members.

In the drawing, the numeral 7 indicates a doll head having openings 8 and 9 for eyes. The eyes which register with said openings are indicated by 10 and 11 and are 55 formed integral, preferably, with arms or levers 12 and 13, respectively, positively con-

nected at their ends by a counterweight 14. The eyes 10 and 11 carry ears 15 and 16, respectively, also upper and lower stops 17, 17 and 18, 18, respectively. The eye members 60 are pivotally mounted on a support or frame consisting of a bar 19 and arms 20, 21 extending rearwardly therefrom. The bar 19 passes through openings in the ears 15 and 16 and arms 12 and 13. The eye-members 65 are free to swing upon said bar, under the action of the counterweight 14, to open or close.

As has been stated, one of the objects of the invention is to provide means to properly position the eyes relatively to the openings 8 and 9. As the bar 19 is located centrally of the eye-ball portion 22 of each eye-member, and the said eye-ball portions are in turn located centrally of their respective 75 openings, it follows that the bar 19 must be located centrally of said openings, which is the proper position. Unless the bar 19 is located in such position the eyes will not be positioned properly with respect to the openings 8 and 9. To cause the bar 19 to be thus positioned without the necessity of manipulating same after the eyes are placed in the head, I provide an alining block 23 which is located between the eye openings as 80 shown. The block 23 is provided with a slot 24 of sufficient depth to cause the bar 19 to assume a position in horizontal alinement with the horizontal center-line of the eye-openings 8 and 9 when said bar is forced to 85 the end of said slot. While the block 23 is a positioning element it also acts in conjunction with anchorage-blocks 25 to maintain the frame in position. The blocks 25 are each provided with a pocket 26 to receive the 90 ends of the arms or extensions 20 and 21. The eye-support is not secured in position by any other elements than said block and can be easily removed. The frame or eye-support is made out of wire that can be 95 easily flexed or bent. In other words, I do not employ wire having any spring action, as I do not depend upon resiliency to hold the frame in place.

The frame and eyes carried thereby will 105 be inserted through the neck-opening 27 and the parallel arms or extensions 20 and 21 slightly bent to cause them to engage the pockets 26 in the blocks 25, after which they can be straightened and the bar 19 caused 110 to enter the slot 24. The alining block 23 will position the frame so as to cause the

eyes to properly aline with the openings 8 and 9.

A further feature of my invention is the manner of connecting the eye-member arms 5 12 and 13 by the counterweight 14.

As can be seen in Figs. 5 and 6, the arms 10 of the eye-members are provided with outstanding prongs 28, 29 and 30 to form a retainer to receive the ends of a primary connecting bar 31. To assemble the eye-members a bar, such as 31, preferably of lead, will be inserted, at each end, into a retainer formed by the above mentioned prongs at 15 the end of the arms of the eye-members.

15 The prongs may be pressed against the bar to hold same. After the above operation has been performed, the connected ends of said arms, together with the connecting bar, will be dipped into molten lead in a suitable 20 mold and left until the molten lead has cooled, after which a block forming the counterweight 14 will be formed. By this means I am enabled to provide an extremely durable structure, as the eye-members will 25 be connected by a solid mass of metal having embedded therein the ends of the arms which carry the eye-members.

Having now described my invention, what I claim is:—

30 1. In combination with a doll head having openings for eyes, movable eye-members, a frame therefor pivotally connected to said eyes centrally thereof, means carried by the doll-head to engage said frame at its 35 ends, and means also carried by the head to engage said frame intermediate its ends and arranged to position the eyes centrally of the openings therefor.

2. In combination with a doll head having 40 openings for eyes, a frame consisting of a horizontal bar-member, parallel arms extending therefrom, means carried by the head to engage said arms at the ends thereof, means also carried by the head to engage 45 said bar and position same in horizontal alinement with the horizontal center-line of the said openings, and eye-members pivotally supported by said bar in alinement with the openings therefor.

3. In combination with a doll head having 50 openings for eyes, a frame consisting of a horizontal bar-member, parallel arms extending therefrom, blocks carried by the head at each side thereof and provided with pockets to receive the ends of said arms, a 55 block carried by the head and located between the eye-openings, means carried by said block to engage said parallel bar arranged to position said bar in horizontal alinement with the horizontal center-line of 60 said openings, and eye-members pivotally supported by said bar in alinement with said openings.

4. In combination with a doll head having 65 openings for eyes, a frame consisting of a horizontal bar-member, parallel arms extending therefrom, blocks carried by the head at each side thereof and provided with pockets to receive the ends of said arms, a 70 block carried by said head and located between the eye-openings provided with a slot to engage said horizontal bar, the depth of said slot being sufficient to cause said bar to aline with the horizontal center-line of the eye openings and eye-members pivotally 75 supported by said horizontal bar in alinement with said openings.

5. Eye-members for dolls comprising eye-ball portions, arms extending therefrom, and a weight at the free ends of said arms, 80 the said ends of said arms being molded into said weight, said arms being provided with openings adjacent the eye ball portions for the passage of a pivotal support.

6. The method of connecting the members of a pair of movable eyes for dolls, to form a unitary structure consisting in connecting said members at one end by a temporary connecting bar, and finally dipping the said connected ends in a mold containing 90 molten lead, and allowing same to harden.

Signed at New York city, N. Y., this 23 day of October, 1918.

BRUNO PELZ.
